UNITED STATES PATENT OFFICE.

OSCAR V. PAYNE, OF CLEVELAND, OHIO, ASSIGNOR TO AUTO-ORDNANCE CORPORATION, OF NEW YORK, N. Y., A CORPORATION OF NEW YORK.

GUN MECHANISM.

1,363,613.

Specification of Letters Patent. Patented Dec. 28, 1920.

Application filed June 29, 1920. Serial No. 392,765.

To all whom it may concern:

Be it known that I, OSCAR V. PAYNE, a citizen of the United States, and resident of Cleveland, in the county of Cuyahoga and State of Ohio, have invented new and useful Improvements in Gun Mechanism, of which the following is a specification.

This invention relates to firearms and more particularly to a new and improved 10 ejector and ejector securing device, the securing device being of a type readily assembled or dismantled without the use of tools and combining with its function of securing the ejector that of securing in place 15 other adjacent and related portions of the gun.

One of the most important requirements of modern firearms is ease and rapidity of take down or dismantling and of assembly. 20 In line with this requirement it is highly desirable to limit the number of parts and particularly the number of fastening elements. These elements should be capable of manipulation without tools. Another important requirement lies in the limitation of weight and obviously this requirement is attained 25 by limiting both number and size of parts.

It is essential in the use of automatic or semi-automatic arms where the bolt action 30 takes place at a very high linear velocity that an ejector be provided which is equally quick in its action. A positively operated ejector of the bell-crank or similar well known type is objectionable for the reason that an element of its small size and small available 35 pivot area is incapable of long standing up under the heavy and sudden opposite stresses set up in its actuation and in the ejection of the cartridge forced against it.

40 It is an object of my invention to provide a new and improved ejector and ejector retaining means, the latter also functioning in retaining other portions of the gun structure and being of a type readily dismantled 45 and assembled without the use of tools. It is a further object to provide an ejector which is rapid in operation and effective in use, which is composed of but few and simple parts and is relatively inexpensive to manufacture. Other and further objects 50 will appear as the description proceeds.

I have illustrated a preferred embodiment of my invention in the accompanying drawings in which—

Figure 1 is a horizontal section, partly 55 broken away, showing my invention applied to a gun, the bolt being closed;

Fig. 2 is a side view of the ejector retaining device;

Fig. 3 is a bottom view of Fig. 2;

Fig. 4 is a perspective view of the ejector;

Fig. 5 is a view similar to Fig. 1 but showing the bolt open;

Fig. 6 is an end view of the bolt; and

Fig. 7 is a side view of a portion of the receiver.

I have illustrated my improved ejector and ejector retainer as applied to a gun described and claimed in my application Serial No. 353,704, filed Dec. 18, 1919. The 70 gun comprises the barrel 11, receiver 12, tubular locking member 13, bolt 14, bolt handle 15, extractor 16, firing pin 17, sleeve 18, recoil housing 19, shutter 20, recoil spring 21 and recoil buffer 22. The bolt is provided 75 with locking lugs 23 which are adapted to coact with similar lugs upon the locking sleeve 13.

The receiver is provided with the lateral ejection opening 24. As shown in Fig. 7, the 80 side of the receiver is provided with two spaced circular openings, the rearward opening 25 and the middle threaded opening 26, and also with a forward opening 27 the outer portion of which is circular in cross 85 section. This opening 27 is not cut all of the way through the heavier portion of the receiver forward of the locking sleeve 13 but opposed lugs 28 are left in place to guide the ejector in its motion.

The forward face of the bolt as shown in Fig. 6, is intersected by the ejector slot 29. The bolt face in the figure is shown in its closed position, but when opened the bolt is rotated approximately 110° in the clockwise 95 direction and the slot 29 will be located horizontally as shown in Fig. 5 when the bolt is retracted.

The ejector 30 comprises the lower tubular body 31 and the upper diametrically extending ejection fin 32. The ejector is pressed upward by the coil spring 33, the base of which is seated in the arcuate cavity 34 in the ejector retainer or catch 35. The central stud 36 is secured to the receiver by 100 being threaded into the opening 26. While obviously the end of the ejector securing device may be secured in place on the receiver

by any desired form of coacting elements, in the preferred form shown in the drawing it is secured to the receiver by means of the stud 37 fitting the opening 25 in the receiver. 5 The stud 36 has its lower portion threaded and its upper portion smooth and somewhat reduced in size, the threaded portion screwing into the opening 26 in the receiver and the smooth portion fitting into an opening 10 26' in the locking sleeve as shown in Figs. 1 and 5. The portion of the catch between studs 36 and 37 is sufficiently flexible so that the stud 37 may be sprung into or out of the opening 25 after the stud 36 has been threaded into place. As is shown in Figs. 1 and 5 the stud 37 extends through the receiver 12 and into an opening 25' in the forward portion 15 of the recoil housing 19.

In assembling the ejector and its retainer 20 upon the receiver, the stud 36 is screwed into the opening 26 until it is slightly in advance of its normal position, in a clockwise direction as the receiver is viewed in Fig. 7. The ejector 30 is now inserted between 25 the lugs 28 and the spring 33 is inserted in the cavity on the base of the ejector and pressed inward. The ejector retainer is then rotated backwardly until the base of spring is seated in the arcuate cavity 34 and the lug 30 37 is snapped into place.

When the breech is in its closed in position as shown in Fig. 1, the nose of the ejection fin rides upon the cylindric surface of the bolt 14, the spring 33 being compressed. 35 During the latter portion of the rearward movement of the bolt the ejector rides up the slot 29 and assumes the position shown in Fig. 5 and contacts with and ejects the cartridge through the opening 24, in the receiver. 40

The ejector is comparatively light and its inertia is insufficient to retard its movement under the impulse of the spring 33 even when that spring is made relatively small. 45 The ejector is therefore very rapid in its action and will operate satisfactorily even with bolts having exceedingly high linear velocity of movement.

The locking sleeve 13, which is threaded 50 into the receiver is retained against rotation by the lug 36 and the recoil housing 19 which is held to the receiver by interrupted threads is retained against rotation by the lug 37. The ejector retainer thus has a 55 triple function in retaining locked in place the ejector, locking sleeve and recoil housing. The retainer may be readily and quickly removed and replaced without the aid of tools and this greatly facilitates the 60 dismantling or assembly of the entire piece.

I claim:

1. In a gun, a receiver having an ejector opening extending through its wall, a separate retaining device for the ejector lying 65 along the outer wall of the receiver, and

means for interengaging said device with said receiver at a point spaced away from said opening.

2. In a gun, a receiver, having an ejector opening extending through its wall, a retaining device for the ejector lying along the outer wall of the receiver and having a portion adapted to cover the ejector opening, the covering portion being disposed substantially wholly outside said opening 75 and having a cavity adapted to be alined with the opening.

3. In a gun, a receiver, having an ejector opening extending through its wall, a retaining device for the ejector lying along the outer wall of the receiver and having a portion adapted to cover the ejector opening, the covering portion having a cavity adapted to be alined with the ejector opening, the cavity extending laterally through 80 a side of the retaining device whereby the portion may be moved to retain the ejector after the latter has been inserted in the opening.

4. In a gun, a receiver, an ejector fitted 90 therein, and a restraining device for the ejector, the ejector interfitting in a cavity in the restraining device, said cavity having sufficient depth to permit the ejector to move longitudinally therein and having an opening 95 in one side to permit lateral movement of the ejector and device relatively to each other.

5. In a gun, a receiver having a circular opening extending inwardly partially 100 through the wall thereof and a slot extending from the bottom of the opening through the remaining thickness of the wall, an ejector having a circular body slidably fitting in said opening and a flat nose projecting through said slot, and a retainer separate from said ejector for retaining the ejector in said opening.

6. In a gun, a receiver, an ejector fitted 110 radially therein, and a retaining device for the ejector adapted to be attached to the receiver by means of a lug threaded into the receiver, the retaining device having an extended resilient portion adapted to be snapped into engagement with a co-acting 115 portion of the receiver after the threaded lug has been screwed into the receiver.

7. In a gun, a receiver, a locking sleeve associated therewith, an ejector fitted therein, a member adapted to retain the ejector 120 in the receiver, the member being attached to the receiver by means of a lug threaded into the receiver, the retaining device having an extended resilient portion with a second lug thereon adapted to be snapped 125 into an opening in the receiver after the threaded lug has been screwed into the receiver, the threaded lug serving to retain the locking sleeve associated with the receiver.

8. In a gun, a receiver, a locking sleeve 130

- and a recoil housing associated therewith, an ejector fitted therein, a member adapted to retain the ejector in the receiver, the member being attached to the receiver by means of a lug threaded into the receiver, the retaining device having an extended resilient portion with a second lug thereon adapted to be snapped into opening in the receiver after the threaded lug has been screwed into the receiver, the threaded lug serving to retain the locking sleeve associated with the receiver, and the second lug serving to retain the recoil housing associated with the receiver.
9. In a gun, a receiver, a locking sleeve associated therewith, an ejector and an ejector retaining device, the ejector retaining device also serving to retain the locking sleeve in association with the receiver.
10. In a gun, a receiver, a locking sleeve and recoil housing associated therewith, an ejector and an ejector retaining device, the ejector retaining device also serving to retain the locking sleeve and recoil housing in association with the receiver.
11. In a gun, a receiver, an ejector fitting in an opening in said receiver and retaining means for the ejector adapted to be pivotally associated with the receiver at a point spaced from the ejector opening and arranged to extend over said opening to retain the ejector in the opening.
12. In a gun, a receiver, an ejector fitting in an opening in said receiver and retaining means for the ejector adapted to be pivotally associated with the receiver adjacent the ejector opening, the retaining means being formed with an ejector retaining cavity laterally extended through the side of the retaining means whereby it may be rotated into engagement with the ejector.
13. In a gun, a receiver, an ejector fitting in an opening in said receiver and retaining means for the ejector adapted to be pivotally associated with the receiver adjacent the ejector opening, the retaining means having an extended resilient portion with a lug adapted to co-act with the receiver to retain the retaining means in predetermined position.

Signed by me at Cleveland, Ohio, this 24th day of June, 1920.

OSCAR V. PAYNE.
